UNITED STATES PATENT OFFICE.

IRVING ORNSTEIN AND JOSEPH MEVORAH, OF NEW YORK, N. Y.

DESIGN FOR A CHARM.

Application filed January 10, 1925. Serial No. 11,989. Term of patent 7 years.

To all whom it may concern:

Be it known that we, IRVING ORNSTEIN and JOSEPH MEVORAH, citizens of the United States of America and Turkey, respectively, and residents of the city of New York, borough of Manhattan, in the county and State of New York, United States of America, have invented a new, original, and ornamental Design for a Charm, of which the following is a specification, reference being had to the accompanying drawings, forming part thereof.

We claim:

The ornamental design for a charm, as shown.

IRVING ORNSTEIN.
JOSEPH MEVORAH.
